UNITED STATES PATENT OFFICE.

JOHN R. BEMIS, OF SPRINGFIELD, MASSACHUSETTS.

TRAVELING CASE.

Application filed August 12, 1922. Serial No. 581,386.

To all whom it may concern:

Be it known that I, JOHN R. BEMIS, a citizen of the United States of America, residing at Springfield, county of Hampden, 5 State of Massachusetts, have invented certain new and useful Improvements in Traveling Cases, of which the following is the specification.

This invention relates to improvements in 10 traveling cases in which the two sections are pivotally connected together at their ends, and each of the sections are divided into a suitable number of compartments for receiving and retaining in place the different articles necessary for traveling purposes.

One of the sections is preferably provided 15 with a foldable cover for retaining the articles in place. Suitable fastening and handle carrying devices are also provided. Other objects and nature of the invention 20 will be fully described in the body of the specification and particularly pointed out in the claims appended hereto.

Referring to the drawings:

25 Fig. 1 is a plan view of the interior of the two sections when turned into an open position, showing the arrangement of the compartments.

Fig. 2 is a vertical longitudinal sectional 30 view on the line 2—2 of Fig. 1 showing the interior doors in sections which are located in the interior of the two sections in closed position and in dotted lines in open position.

35 Fig. 3 is a perspective view of the two hinged sections in partially an open position showing the compartments of each section and the door or lid located therein for closing the compartments, and

40 Fig. 4 is a perspective view showing the two sections in folded position with the carrying handles in operative position and illustrating the package carrier idea associated with the carrying handles and the straps 45 for holding the two sections together.

Referring to the drawings in detail:

1 and 2 designate the two sections of the traveling case which are hinged together as indicated at 3. The hinges are located at 50 the ends of the two sections so that they will open lengthwise rather than transversely, which is the usual way in which traveling cases are opened. The interior of the section 1 is formed with a compartment 4 preferably at the lower or bottom portion of this section. 5 indicates the partition which

forms an additional and adjacent compartment 6. The compartment 4 is closed by means of the hinged lid 7. The compartment 6 is preferably designed for receiving shirts the length of which is substantially equal to the folded bosom of the shirt front and the compartment 4 is preferably designed for receiving rubbers and a foldable umbrella.

65 Referring to the construction of the section designated by the reference numeral 2, the interior of which is divided into compartments indicated at 8, 9, 10, 11, and 12 by means of the partitions 13, 14, 15, 70 and 16. These compartments are closed by means of the lid 17 which is hinged to section 2 as indicated at 18. This lid is of a size to cover all of these compartments. This lid, when in a closed position is normally 75 below the upper surface 19 of this section and is held in its closed position by any suitable means as a latch 20. 21 indicates a hand opening in the lid 17 for swinging it from its closed to open position, as indicated by the dotted lines 17'. The compartment 8 is preferably designed for receiving a case of toilet articles, as brushes, combs, and other articles. Compartment 9 is for receiving socks, compartment 10 is 85 for receiving handkerchiefs, compartment 11 for neckties, and compartment 12 for collars.

80 By moving the lid 17 into its closed position the various articles in the compartments 90 in this section will remain in place without displacement when the traveling case is in use or turned in a vertical position.

It is obvious that this arrangement for placing the different articles enables the 95 user to always have these articles so that they can be readily accessible without disturbing the other articles in the various compartments.

Reference numerals 17² and 17³ designate 100 pockets in the lid 17 for receiving stationery or traveling cap as shown.

Referring now to the construction for carrying the case.

The two sections 1 and 2 are normally 105 retained in closed position by means of the strap 22 which passes around the two sections and through the retaining bands or clips 23. Attached to the upper ends of each of the sections are the strips of leather or 110 other suitable material, 24 and 25. These strips are made sufficiently long to extend

above the upper ends of the two sections and are provided with the carrying handles 26 and 27. These strips 24 and 25 are of sufficient length to receive packages, indicated at 28 and 29 and located between the sections 1 and 2 and the carrying straps, and if desired a package may be placed on the upper ends of the two sections and within the carrying straps or pieces 24 and 25 10 as indicated at 29'. 30 indicates suitable securing means for normally retaining the side pieces 24 and 25 in position to prevent them from falling down. The strips of leather or other suitable material are secured 15 to the sections 1 and 2 by means of the rivets or other devices 31. A strap 32 is detachably secured to the bottom of the compartment 11 by means of glove fastening devices 33. It is used for securing neckties 20 in place.

What I claim is:

1. A traveling case for the purpose described comprising two box-like sections hinged together at one of their ends, one 25 section having a compartment at its hinged end portion designed for receiving rubbers, a cover or lid for closing the compartment, each section having strips connected to their outer ends and extending beyond said ends 30 and carrying handles secured to the strips.

2. A traveling case for the purpose described comprising two box-like sections hinged together at one of their ends, one section having a compartment at its hinged 35 end portion designed for receiving rubbers, a cover or lid for closing the compartment, each section having strips connected to their outer ends and extending beyond said ends and carrying handles secured to the strips, 40 said strips being attached to the sections near their outer ends to provide a space for receiving a package between the side portions of the sections and the strips.

3. In a traveling case, the combination, of 45 two box-like sections, hinges for connecting the same together at one of their ends, one section having a plurality of compartments therein, a lid or cover for closing the compartments, the other section having a com-

partment at one end and a cover for closing 50 the same, a strap for retaining the sections in closed position, and devices connected to the sections for carrying the case, said devices being connected to the sections for providing a bundle receiving space at the 55 outer ends of the section.

4. In a traveling case, the combination, of two box-like sections, hinges for connecting the same together at one of their ends, one section having a plurality of compartments 60 therein, a lid, or cover, for closing the compartments, the other section having a compartment at one end and a cover for closing the same, a strap for retaining the sections in closed position, and devices connected to the sections for providing a bundle receiving space at the outer ends of the section, said devices also providing means 65 for inserting and retaining packages at the outer upper side surface of the sections. 70

5. In a traveling case, the combination, of two box-like sections, hinges for connecting the same together, one of the sections having compartments suitably formed for receiving the following articles; namely; toilet articles, socks, handkerchiefs, collars, and neckties, a lid or cover, secured to this section for closing the compartments, the other section having two compartments suitably 75 formed for receiving rubbers and shirts, respectively, a device for retaining the sections in closed position, and devices attached along the upper outer sides of the sections for carrying the case, said devices permitting articles to be inserted and retained at the 80 upper outer side surfaces of the sections. 75

6. A carrying device for a traveling case, the sections of which are hinged together at one of their ends, the carrying device comprising a strip attached to the upper 85 outer surface of each section and below their outer ends to provide pocket-like receptacles for receiving articles in the spaces between said surfaces and the carrying strips and for providing a space at the outer ends of the 90 sections and between the strips for receiving articles or a package, as described. 95

JOHN R. BEMIS.
